(57) **CLAIM**

The ornamental design for a tubing and cable organizing device, as shown.

DESCRIPTION

FIG. 1 is a perspective view of a preferred embodiment of the ornamental design for a tubing and cable organizing device;

FIG. 2 is a reverse perspective view of a preferred embodiment of the ornamental design for a tubing and cable organizing device;

FIG. 3 is a front view of a preferred embodiment of the ornamental design for a tubing and cable organizing device;
FIG. 4 is a rear view of a preferred embodiment of the ornamental design for a tubing and cable organizing device;
FIG. 5 is a top view of a first preferred embodiment of the ornamental design for a tubing and cable organizing device;
FIG. 6 is a bottom view of a preferred embodiment of the ornamental design for a tubing and cable organizing device;
FIG. 7 right side view of a preferred embodiment of the ornamental design for a tubing and cable organizing device; and,

FIG. 8 left side view of a preferred embodiment of the ornamental design for a tubing and cable organizing device.

1 Claim, 6 Drawing Sheets
